UNITED STATES PATENT OFFICE.

CHARLES H. SHERWOOD, OF UTICA, NEW YORK, ASSIGNOR OF ONE-HALF
TO HENRY C. LYMAN, OF SHERBURNE, NEW YORK.

AUTOMATIC PNEUMATIC RAILWAY-GATE.

SPECIFICATION forming part of Letters Patent No. 565,929, dated August 18, 1896.

Application filed August 12, 1895. Serial No. 559,017. (No model.)

To all whom it may concern:

Be it known that I, CHARLES H. SHERWOOD, of Utica, in the county of Oneida, in the State of New York, have invented new and useful 5 Improvements in Automatic Pneumatic Railway-Gates, of which the following, taken in connection with the accompanying drawings, is a full, clear, and exact description.

This invention relates to the class of railway-gates which are operated automatically by an engine or train of cars approaching and passing the portion of the railway guarded by said gates, and is designed specially for double-track railways.

15 The invention has special reference to the gates shown and described in my Patent No. 526,872, dated October 2, 1894, which consists of air-pumps and relief-valves actuated by a passing train and connected by air-conduits 20 with an air-cylinder, the piston of which is operated by the pressure of the admitted air and imparts motion to mechanism which operates the gates, the whole constituting an automatic pneumatic railway-gate.

25 My present invention consists in providing two main air-cylinders within the gate-standard, preferably in a vertical position, and a set of gears for each cylinder, actuated by its piston-rod, which is provided with teeth, 30 a set of gears for operating the bell, adapted to be operated by both piston-rods, a set of air-pumps for each cylinder remote from the gate in opposite directions and communicating with the bottom of interior thereof, a set 35 of air-pumps for each cylinder adjacent to the gate communicating with the top of the interior thereof, a relief-valve communicating with the top of the interior of both cylinders, two supplemental or relief cylinders 40 adjacent to the main cylinders, either of whose piston-rods actuates said relief-valve, a set of relief-valves communicating with the bottom of the interior of each main cylinder and its adjacent relief-cylinder and operated 45 by the adjacent pumps, and track instruments actuated by a passing train operating all of said pumps; and the invention consists in the novel details of the construction, as hereinafter fully described, and set forth 50 in the claims.

In the accompanying drawings, Figure 1 is

a vertical transverse section of a gate-standard, showing the mechanism for operating the gate-arm and the arrangement of the air-cylinders. Fig. 2 is a horizontal transverse section of the same. Figs. 3 and 4 are enlarged side views of the sets of gears which operate the gate-arm. Fig. 5 is an enlarged side view of the gears which operate the alarm-bell. Fig. 6 is a plan view of the four gate-stands, showing the arrangement of the air-pumps and the relief-valves operated thereby, and the track instruments which operate the same, and the pipe connections between the same. Fig. 7 is an enlarged detail view 65 of one of the pumps and relief-valves operated thereby and the track instrument operating the same. Fig. 8 is an enlarged detail view of the bracket on which are supported the relief-cylinder and plunger which operates 70 the relief-valve which communicates with the upper end of the main air-cylinders. Fig. 9 is an enlarged detail view of the locking mechanism which holds the gate in its open and closed position. Fig. 10 is a detail view 75 of one of the gears mounted loosely on the main shaft and cam which operates the lock. Fig. 11 is a transverse section of the gate-standard, showing the arrangement of the main air-cylinders, relief-valve, and relief- 80 cylinders. Fig. 12 is a detail plan view of the latch of the aforesaid locking mechanism; and Figs. 13 and 14 are edge views, respectively, of the aforesaid gear and collar adjacent thereto.

85 Similar letters of reference indicate corresponding parts.

A represents the hollow gate-standard, across which extends the main shaft A', journaled in suitable bearings a'' a'', and on the 90 ends of said shaft are secured the vertically-swinging gate-arms A'' A''.

Within the standard A and arranged in vertical position are two main air-cylinders B and B', having their piston-rods C and C' 95 provided, respectively, with ratchet-bars u' and u''. Within the standard are four vertical plates arranged in pairs, as I and I' and I'' I'''. Secured to the plates I and I' are three horizontal shafts 1, 3, and 4. Upon the shaft 1 is mounted a gear e, which meshes with the ratchet-bar u' on the piston-rod C of the main

cylinder B, and upon one end of said shaft is secured a gear d. By means of the intermediate gears c and b motion is transmitted to the gear a, mounted loosely on the main shaft A'.

5 On the inner side of the gear a is formed a lug h, and on the opposite side is secured a cam plate or disk g. Adjacent to the inner side of said gear is a collar f, secured to the main shaft A', which collar is formed with a lug i, 10 corresponding to the aforesaid lug, and is also formed with two notches h'' h''' in its periphery, as shown in Fig. 9 of the drawings.

Secured to the gate-standard is a support to which is pivoted a latch t, formed with the 15 hooks t''' t'''. Said latch rests by gravity with the hook t' on the cam g and the hook t''' in one of the notches h''' to lock the gate-arm in its open position, as shown in Figs. 9 and 10 of the drawings.

20 In the upward movement of the piston-rod C the ratchet-bar u' thereon turns the gear e, thereby rotating the shaft 1, and by means of the gears c and b the gear a is turned and the lug h thereon engages the lug i on the collar f, thereby turning the shaft A' to swing the gate-arm to its closed position.

25 There is a lost motion between the two lugs during which the cam-disk g raises the hook t''' from the notched collar f, which allows the shaft A' to turn. When the gate has reached its extreme closed position, the cam-disk g has made a complete revolution, which allows the latch t to drop with its hook t''' in the other notch h''' in the collar f to lock the gate-arm 30 in its closed position, said collar having made one-quarter of a revolution.

35 In the downward movement of the piston-rod C the aforesaid set of gears is given a reversed motion whereby the cam-disk g again raises the hook t''' of the latch t from one of the notches h''' of the notch-collar f, thus allowing the shaft A' to turn to swing the gate-arm to its open position.

40 Secured to the plate I'' and I''' is a horizontal shaft 2, having secured thereon a gear e', which meshes with the ratchet-bar u'', secured to the piston-rod C' of the other main cylinder B'.

45 On one end of the shaft 2 is a gear c', and by means of the intermediate gear b' motion is transmitted to another gear a', mounted loosely on the main shaft A'. On the inner side of said gear a' is formed a lug h' and on its outer face a cam plate or disk g'. Adjacent to the inner side of said latter gear and secured to the main shaft is another collar f', provided with a lug i', adapted to engage the lug h' on the gear a'.

50 In the upward movement of the piston-rod C' the gear e' is turned, thereby rotating the shaft 2 and gear c', secured on its end, and by means of the intermediate gear b' the gear a' on the main shaft is rotated. During the rotation of the gear a' the lug h' thereon engages the lug i' on the collar f', thereby turning the main shaft A'.

55 There is a lost motion between the lugs h' and i', during which the cam-disk g' on the

gear a' raises the hook t''' of the latch t, thereby lifting the hook t' from notched collar f, thus allowing the shaft A' to turn to 70 swing the gate-arm to its closed position. When the gate-arm has reached its extreme closed position, the cam-disk g' allows the hook t''' to drop into the other notch h''' of the aforesaid collar, thus locking the gate-arm in said position. In the downward movement of the piston-rod C' the said latter set of gears is given a reversed motion, whereby the cam-disk g' again raises the hook of the latch t, thus allowing the shaft A' to 75 turn in the opposite direction to swing the gate-arm to its open position. When the arm has reached its extreme open position, said cam-disk allows the hook t''' to drop into the first-mentioned notch h''' of the collar f, thereby locking the gate-arm in its open position.

80 The object of providing the lost motions between the gear a and collar f and between the gear a' and collar f' is to allow the alarm-bell B'' to be rung before the gates move to their closed position, which is accomplished by the following mechanism: On the shafts 1 and 2, respectively, and loosely mounted are the gears j and j', which are connected by the 85 intermediate gears k and l, secured to the plate e'', provided with the segmental slot e''', and a bolt e''', passing through said slot and the plate I''', by which to adjust the latter gears. On the shaft 1, adjacent to the gear j, is secured a ratchet-wheel j'', and on the adjacent side of said gear is pivoted a pawl l', held in engagement with said ratchet-wheel by a spring k', secured to said gear.

90 In the upward movement of the piston-rod C it meshes with the gear e, which rotates the shaft 1 and by means of the ratchet-wheel j'' turns the gear j, which meshes with the gear m, secured to the shaft 3. On said shaft is also secured a gear n, which meshes with the gear n', secured to the shaft 4, and on the shaft 4 is secured a fly-wheel o, having secured to one of its sides a frame o', provided with the sliding bell-hammers p p', which strike the bell B'', secured to the exterior of the gate-standard A, said standard being provided with a hole or slot p', through which said hammers project, and over said bell is provided a shield q. On the upward movement of the piston-rod C' the bell-ringing mechanism is operated by means of the gear e' on the shaft 2, meshing with the ratchet-bar u'' on said piston-rod, turning the gear j', secured to said shaft, and by means of the intermediate gears k and l motion is transmitted to the gear j.

95 The shaft 2 is provided with a ratchet-wheel j'' adjacent to the gear j', and on the adjacent side of said gear is pivoted a pawl l'', held in engagement with said ratchet-wheel by a 100 spring k'', secured to said gear. Said ratchet-wheel j'' and pawl l'' are arranged in reverse position from the ratchet-wheel j'' and pawl l' on the gear j in order to allow the pistons

C and C' to descend without turning said gears and operating the bell-ringing mechanism.

The hereinbefore-described intermediate gears b and c are pivoted to the plate d', which is pivoted to the plate I and provided with a segmental slot d''' and adjustable by means of a bolt d''', passing through said slot and plate I.

10 The intermediate gear b' is pivoted to a plate f'', mounted loosely on the shaft 2 and adjacent to the plate I''' and provided with a segmental slot f''', and is adjustable by means of a pin or bolt f''', passing through said slot and plate I'''.

Remote from the gate-standard A and along one of the railway-tracks is arranged a set of air-pumps J J, operated by track instruments actuated by a passing train. Said instrument consists of a horizontal shaft 5, extending from the railway-track to the pump and provided on its end adjacent to the track with a vertical arm 6 and on its end adjacent to the pump with a horizontal arm 7, which latter arm bears against the under side of an annular horizontal plate 8, secured to the lever end of the piston-rod 9 of the pump, as shown in Fig. 7 of the drawings.

Adjacent to the main air-cylinders B and B', respectively, are two supplemental or relief cylinders D and D', supported on a bracket H. On the upper portion of said bracket is formed a guide m', and above said guide is located a relief-valve E, which communicates by means of the pipes v and v' with the top of the interior of the main air-cylinders B and B'. In said guide slides an inverted-T-shaped plunger G, which is axially in line with the stem o'' of said relief-valve 40 in order to push up the same to open the valve, which plunger is operated by the piston-rods n' and n'', respectively, of the cylinders D and D'.

The operation of my improved gate is as follows: As a train passes the remote air-pumps J J said pumps are operated by the track instruments thereat, whereby air is forced through the pipes 10 and 11 into the bottom of the main cylinder B and at the same time from the pipe 11 through the pipes 12 and 13 into the bottom of the relief-cylinder D, whereby the piston-rod n' thereof operates the plunger G, which opens the relief-valve E and releases the air from the top of the cylinder B and allows its piston to ascend, whereby its rod C by means of the ratchet-bar u', secured thereon, engages the gear e, which turns the shaft 1, thereby rotating the gear d, secured on one end of said shaft, and by means of the intermediate gears c and b motion is transmitted to the gear a, mounted loosely on the main shaft A', as aforesaid. In the movement of the gear a the cam-disk g, secured thereon, raises the hook t' of the latch t, thereby lifting the hook t'' from one of the notches h'' in the collar f, secured to the shaft A', thus unlocking said shaft, to

which the gate-arm a'' is secured, and when the gear a has made one-half revolution the lug h thereon engages the lug i, secured or formed on said collar, to give the shaft and collar one-quarter revolution, thereby swinging the gate-arm to its closed position, when the cam-disk g allows the hook t'' to drop into the other notch h'' of the aforesaid collar to lock the gate-arm in said position.

As the train passes the gates the track instruments thereat are actuated, thereby operating a set of pumps J' J', which pumps operate the relief-valves K K, located at each pump, whereby the air is released from the bottom of both cylinders B and D through the aforesaid pipes. At the same time said pumps force air through pipes 14, 15, and 16 into the top of the main cylinder B, whereby its piston descends and its rod C turns the aforesaid gears and mechanism in the opposite direction, thereby swinging the gate-arm to its open position. Remote from the gate-standard and in opposite direction from the air-pumps J J and alongside of the other track are pumps L L, which are operated by track instruments, actuated by a passing train approaching the gate, and are similar to those which operate the pumps J J. Said pumps L L force air through pipes 17, 18, and 19 into the bottom of cylinders B' and D', thereby raising their pistons, whereby the piston-rod n'' of the cylinder D' operates the plunger G, which pushes up the stem o'' of the relief-valve E, thereby opening the same and releasing the air from the top of the cylinder B', whereby its piston-rod C' by means of the ratchet-bar u'' engages the gear e', which turns the shaft 2, thereby rotating the gear c', secured to one end of said shaft, and by means of the intermediate gear b' motion is transmitted to the gear a', mounted loosely on the main shaft A', as aforesaid. In the movement of the gear a' the cam-disk e', secured thereon, raises the hook t'' of the latch t, thereby lifting the hook t' from one of the notches h'' in the collar f, as aforesaid, thus unlocking the shaft A', and when said gear has made one-half revolution the lug h' thereon engages the lug i' on the collar f' to give the shaft one-quarter revolution, thereby swinging the gate-arm A'' to its closed position, when the cam-disk g' allows the hook t'' to drop into the other notch h'' of said collar to lock the gate-arm in said position substantially in the same manner hereinbefore described.

As the train passes the pumps L' L', adjacent to the gate, they are operated in the same manner as the pumps L L, whereby air is forced through the pipes 20, 21, 22, 15, and 16 into the top of the cylinder B'. At the same time the relief-valves M M, operated by the adjacent pumps, release the air from the bottom of cylinder B' through the pipes 19, 18, and 17 and simultaneously from the cylinder D' through the pipe 24, which leads to pipe 19. By this operation the piston of the cylinder B' descends and its rod C' turns said

latter gears and mechanism in a reverse direction, thereby swinging the gate-arm to its open position, when the same is locked in the manner hereinbefore described.

5 The pipes 10 and 17 are provided with suitable check-valves N, and adjacent to the air-cylinders the pipes are provided with suitable pop-valves O O to relieve any excess pressure.

Although a separate set of gears and sets 10 of independently-operated pumps are provided for each of the main cylinders B and B', when the piston-rod of either cylinder is operated to actuate its set of gears to move the gate-arm to its closed or open position, 15 the set of gears of the other cylinder is actuated by the main shaft A', thereby raising and lowering the piston-rod of said latter cylinder, but said latter set of gears does not assist the other set in raising or lowering the 20 gate-arm, and said latter piston-rod does not start to move at the same instant with the other rod, but remains at rest until the shaft A' has made one-half revolution, owing to the lost motion between the lug on the loosely-mounted gear (a or a', as the case may be) of 25 the latter set and the lug on the adjacent collar secured to the shaft, as aforesaid.

The gears a, b, c, a', b', and c' employed in my improved gate are shown partly in dotted 30 lines, but all of said gears are complete.

All the herein-described mechanism and air-cylinders are provided in one gate-standard only.

In order to operate the gate-arms A'' with all 35 the standards in unison, I mount upon the main shaft A' at each standard a grooved or sprocket wheel F, carrying a chain r, having its ends connected to the upper ends of two vertical rods r' r' by means of turnbuckles 40 r'' r''. The lower ends of said rods are each connected to one of the arms of the bell-crank levers s s, and from said levers, extending, respectively, to a corresponding lever across the street and railway-track, are two 45 horizontal rods s' s'. The piston-rods C and C' of the cylinders B and B' are each provided with a guide b'', secured to the gate-standard A, and in each guide is pivoted a roller c'', forming bearings for said rods.

50 When the pistons of the main cylinders B and B' are moved upward by the air-pressure from the remote pumps J J or L L, the piston-rods C and C' actuate the gears which operate the bell-ringing mechanism, as before 55 stated.

If a train is approaching the gates and passing the remote pumps while another train is passing the gates and adjacent pumps and moving in the opposite direction, said gates 60 are prevented from opening by the approaching train operating said remote pumps which force up the piston of the cylinders D or D', as the case may be, which depends upon the direction in which the approaching train is 65 moving, thereby operating the plunger G, which pushes up the stem o'' of the valve E, opening the same and releasing the air from

the top of the main cylinders B and B', which is being forced therein by the adjacent pumps operated by the passing train, whereby the 70 piston and piston-rod of either cylinder B or B' will not descend and actuate the gears and thereby move the gate-arms. This is one of the most important features of my invention.

What I claim as my invention is— 75

1. In an automatic pneumatically-operated gate for double-track railways, the combination of a gate-arm, two independent sets of gears each adapted to move said arm to and from its closed position, an air-cylinder for 80 each set having its piston-rod actuating its set, two sets of air-pumps remote from the gate in opposite directions along each track and each set communicating with the bottom of the interior of one of the cylinders, a relief-valve communicating with the top of the interior of both cylinders, a set of independently-operated air-pumps adjacent to the gate and along each track both communicating 85 with the top of the interior of both cylinders, a set of relief-valves operated by each of the sets of adjacent pumps and each communicating with the bottom of the interior of one of the cylinders, all said pumps being operated by track instruments actuated by a passing train or engine as set forth. 90

2. In an automatic pneumatically-operated gate for double-track railways, the combination of a vertically-swinging gate-arm, two independent sets of gears each adapted to 100 move said arm to and from its closed position, an air-cylinder for each set and having its piston-rod actuating its set, two sets of air-pumps remote from the gate in opposite directions each communicating with the bottom 105 of the interior of one of the cylinders, a relief-valve releasing the air from the top of both main cylinders, two supplemental or relief cylinders either of whose piston-rods actuates said valve, the cylinders being independently 110 operated by pressure from the two respective sets of remote air-pumps, an independent set of air-pumps along each track and adjacent to the gate and both communicating with the top of the interior of both main cylinders, a 115 set of independently-operated relief-valves adjacent to the gate and along each track and each releasing the air from the bottom of the interior of one main cylinder, and track instruments operating all of said pumps and actuated by a moving train or engine as set forth. 120

3. In an automatic pneumatically-operated gate for double-track railways, the combination of a vertically-swinging gate-arm, two 125 sets of gears each adapted to move said arm to and from its closed position, a vertically-disposed main cylinder for each set having its piston-rod actuating its set, two sets of air-pumps remote from the gate in opposite directions and each communicating with the bottom of the interior of one of the main cylinders, a relief-valve releasing the air at the 130 top of the interior of both main cylinders, a

- plunger operating said valve, a supplemental air-cylinder adjacent to each main cylinder either of whose piston-rods actuates said plunger, said supplementary cylinders being independently operated by pressure from the respective sets of the remote pumps, two sets of air-pumps adjacent to the gate each communicating with the top of the interior of one of the main cylinders, a set of relief-valves operated by each set of the adjacent pumps and releasing the air from the bottom of the interior of the respective main cylinders and their adjacent supplemental cylinder, and track instruments operating all of said pumps and actuated by a passing train or engine as set forth.
4. In an automatic pneumatically-operated gate for double-track railways, the combination of a vertically-swinging gate-arm, two sets of gears each adapted to move said arm to and from its closed position, a main air-cylinder for each set and having its piston-rod actuating its set, a set of air-pumps for the respective main cylinders remote from the gate in opposite directions and communicating with the bottom of the interior thereof, a relief-valve releasing the air from the top of the interior of both main cylinders, an inverted-T-shaped plunger axially in line with the stem of said valve and operating the same, a supplemental air-cylinder adjacent to each main cylinder, either of whose piston-rods actuates said plunger, said supplemental cylinder being independently operated by pressure from respective sets of remote pumps, a guide for said plunger, two sets of air-pumps adjacent to the gate communicating with the top of the interior of both main cylinders, a set of relief-valves operated by each set of adjacent pumps and releasing the air from the bottom of the interior of the respective main cylinders and their adjacent supplemental cylinder, and track instruments operating all of said pumps and actuated by a passing train or engine as set forth.
5. In an automatic pneumatically-operated gate for double-track railways, the combination of a vertically-swinging gate-arm, two sets of gears each adapted to move said arm to and from its closed position, a main air-cylinder for each set having its rod actuating its set, a set of air-pumps for the respective main cylinders remote from the gate in opposite directions and communicating with the bottom of the interior thereof, a relief-valve releasing the air from the top of the interior of both main cylinders, an inverted-T-shaped plunger axially in line with the stem of said valve and operating the same, a supplemental air-cylinder adjacent to each main cylinder, either of whose piston-rods actuates said plunger, said supplemental cylinders being independently operated by pressure from the respective sets of remote pumps, a guide for said plunger, two sets of air-pumps adjacent to the gate communicating with the top of the interior of both main cylinders, a set of relief-valves operated by each set of adjacent pumps and releasing the air from the bottom of the interior of the respective main cylinders and their adjacent supplemental cylinder, and track instruments operating all of said pumps and actuated by a passing train or engine as set forth.
6. In an automatic pneumatically-operated gate for double-track railways, the combination of a standard, a horizontal shaft journaled thereon, a vertically-swinging gate-arm secured on said shaft, two sets of gears each adapted to turn said shaft to swing the gate-arm to and from its closed position, a main air-cylinder for each set having its piston-rod operating its set, separate sets of air-pumps communicating with the top of the interior of both of said cylinders, a relief-valve communicating with the top of the interior of both cylinders, two sets of pumps communicating with the top of the interior of both cylinders, an independently-operated set of relief-valves communicating with the bottom of the interior of each cylinder, track instruments actuated by a passing train and operating all said pumps, mechanism to automatically lock the gate-arm in its closed or open position, and means to automatically unlock the same as set forth.
7. In an automatic pneumatically-operated gate for double-track railways, the combination of a gate-standard, a horizontal shaft journaled thereon, a vertically-swinging gate-arm secured on said shaft, two sets of gears each adapted to turn said shaft independently, an air-cylinder for each set having its piston-rod provided with teeth and actuating its set, a separate set of air-pumps remote from the gate in opposite directions and communicating with the bottom of the interior of the respective cylinders to move their pistons outward to swing the gate-arm to its closed position, a relief-valve releasing the air from the top of the interior of both cylinders and operated by pressure from both of the sets of the remote air-pumps, two sets of independently-operated air-pumps adjacent to the gate and communicating with the top of the interior of both cylinders to move their pistons inward to swing the gate-arm to its open position, a set of relief-valves operated by each of the adjacent sets of pumps and releasing the air from the bottom of the interior of the respective cylinders, track instruments operating all of said pumps and actuated by a passing train or engine, a notched collar secured to the aforesaid shaft, a latch adapted to engage said collar to hold the gate-arm in its open or closed position, and means to disengage said latch from the collar as set forth.
8. In an automatic pneumatically-operated gate for double-track railways, the combination of a standard, a horizontal shaft journaled thereon, a vertically-swinging gate-arm secured on said shaft, two sets of gears each

adapted to turn said shaft to swing the gate-arm to and from its closed position, an air-cylinder for each set having its piston-rod actuating its set, two sets of air-pumps remote 5 from the gate in opposite directions and each communicating with the bottom of the interior of one of the cylinders, a relief-valve releasing the air from the top of the interior of both cylinders and operated by a pressure 10 from each of said sets of remote pumps, two sets of air-pumps adjacent to the gate and each communicating with the top of the interior of both cylinders, a set of relief-valves operated by each of the adjacent sets of pumps 15 and releasing the air from the bottom of the interior of the respective cylinders, a notched collar secured to the aforesaid shaft, a latch adapted automatically to engage said collar to hold the gate-arm in its open or closed position, and a cam operated by each set of gears 20 adapted automatically to disengage said latch as set forth.

9. In an automatic pneumatically-operated gate for double-track railways, the combination of a standard, a horizontal shaft journaled thereon, a vertically-swinging gate-arm secured on said shaft, two independent gears mounted loosely on said shaft, a set of gears actuating each of the aforesaid gears, an air-cylinder for each set having its piston-rod 25 provided with a ratchet-bar and actuating its set, means on said shaft to engage each loosely-mounted gear, two sets of air-pumps remote from the gate in opposite directions and each 30 communicating with the bottom of the interior of one of the aforesaid cylinders, a relief-valve releasing the air from the top of the interior of both cylinders and adapted to be operated by pressure from either set of remote 35 pumps, two independent sets of air-pumps adjacent to the gate and communicating with the top of the interior of both cylinders, a set of relief-valves operated by each of the adjacent sets of pumps and releasing the air 40 from the bottom of the interior of one of said cylinders, a lock holding the gate-arm in its open or closed position, means to automatically unlock the same, and track instruments operating all of said pumps and actuated by 45 a passing train or engine as set forth.

10. In an automatic pneumatically-operated gate for double-track railways, the combination of a standard, a horizontal shaft journaled thereon, a vertically-swinging gate-arm secured on said shaft, a pair of collars secured to said shaft and each provided with a lug on one side, one of said collars being provided with notches, a gear mounted loosely on said shaft adjacent to each collar and each 55 provided with a corresponding lug on one side adapted to engage the lugs on the respective collars with a lost motion between them, a cam-disk secured to the opposite side of each of said gears, a latch pivoted to the standard 60 and formed with two outer hooks lying on the respective cam-disks, and with a central hook by which it engages the aforesaid notched col-

lar, a set of gears operating each of the aforesaid loosely-mounted gears, a main air-cylinder for each set having its piston-rod provided 70 with a ratchet-bar to actuate its set, two sets of air-pumps remote from the gate in opposite directions and each communicating with the bottom of the interior of one of said cylinders, a relief-valve releasing the air from the top 75 of the interior of both cylinders, a plunger operating said valve, a supplemental or relief cylinder adjacent to each main cylinder either of whose piston-rods actuates said plunger, said supplemental cylinder being independently operated by pressure from the respective sets of remote pumps, two independent sets of air-pumps adjacent to the gate and communicating with the top of the interior of both main cylinders, a set of relief-valves 80 operated by each set of adjacent pumps and communicating with the bottom of the interior of one main cylinder, and track instruments operating all of said pumps and actuated by a passing train or engine as set forth. 85

11. In an automatic pneumatically-operated gate for double-track railways, the combination of a standard, a horizontal shaft journaled thereon, two sets of gears each adapted to turn said shaft to swing the gate-arm to 90 and from its closed position, an air-cylinder for each set having its piston-rod actuating its set, two sets of air-pumps remote from the gate in opposite directions and each communicating with the bottom of the interior of one of said cylinders, a relief-valve releasing the air from the top of the interior of both of 95 said cylinders and operated by pressure from either of the sets of remote pumps, two independent sets of air-pumps adjacent to the 100 gate and communicating with the top of the interior of both cylinders, a set of relief-valves operated by each set of adjacent pumps and releasing the air from the bottom of the interior of the respective cylinders, track instruments operating all of said pumps and actuated by a passing train or engine, a groove or sprocket-wheel secured to the aforesaid shaft, a chain running on said wheel, two vertical rods extending downward from the 105 ends of said chain and each connected at the lower end to a bell-crank lever, and a horizontal rod extending from each lever respectively across the street and track as set forth. 110

12. The combination with the improved automatic pneumatically-operated railway-gate consisting essentially of a standard, a vertically-swinging gate-arm supported thereon, two sets of gears each adapted to move said arm to and from its closed position, an air-cylinder for each set having its piston-rod provided with a ratchet-bar and actuating its set, and automatically-operated air-pumps and relief-valves communicating with the top and bottom of the interior of said cylinders to 125 move their pistons, of a guide for each piston-rod secured to the gate-standard, and a roller in each guide back of the rod forming a bearing for the same as set forth and shown. 130

13. In an automatic pneumatically-operated gate for double-track railways, the combination of a vertically-swinging gate-arm, two sets of gears each adapted to move said arm to and from its closed position, an air-cylinder for each set having its piston-rod provided with a ratchet-bar to actuate its set, an alarm-bell, mechanism to ring the same, a separate set of gears to operate said mechanism and adapted to be actuated by either piston-rod, two sets of air-pumps remote from the gate in opposite directions each communicating with the bottom of the interior of one of said cylinders, a relief-valve releasing the air from the top of both cylinders and operated by pressure from the respective sets of remote pumps, two sets of air-pumps adjacent to the gate each communicating with the top of the interior of both cylinders, a set of relief-valves operated by each adjacent set of pumps and each set releasing the air from the bottom of the interior of one cylinder, and track instruments operating all of said pumps and actuated by a passing train or engine as set forth.

14. The combination with the gate-standard A, of a main horizontal shaft A' extending across the same, vertically-swinging gate-arms A'' secured on the ends thereof, gears a and a' mounted loosely on said shaft, shafts 1 and 2 suitably supported in said standard, gears d and e on the shaft 1, similar gears c' and e' on the shaft 2, and air-cylinder B having its piston-rod C provided with a ratchet-bar u' actuating the gear e, a corresponding cylinder B' having its piston-rod C' provided with a ratchet-bar u'' actuating the gear e', intermediate gears b and c between the gears a and a' and an intermediate gear b' between the gears a' and c', suitable connection between the loose gears a and a' and the shaft A',

gears j and j' mounted loosely respectively on shafts 1 and 2, a ratchet-wheel j'' secured on the shaft 1 adjacent to the gear j, a similar ratchet-wheel j''' on the shaft 2 adjacent to 45 the gear j', pawls l' and l'' secured respectively to the sides of said latter gears, and engaging said ratchet-wheels, said pawls faced in opposite directions, springs k' and k'' for the respective pawls holding the same in 50 engagement, intermediate gears k and l between the gears j and j', a suitably-supported shaft 3, a gear m on one end of the latter shaft and meshing with the gear j, a gear n on the opposite end, a gear n' mounted on a 55 shaft 4 meshing with the gear n, a fly-wheel o on the shaft 4, a frame o' secured to said fly-wheel, bell-hammers p p secured to said frame, a bell B'' secured to the gate-standard, and air-pumps and relief-valves controlling 60 the movement of the pistons of said cylinders B and B' as described and shown.

15. The combination with the gate-standard A, a bracket H secured thereto, cylinders D and D' supported on said bracket, a guide m' 65 on the bracket, an inverted-T-shaped plunger G sliding in said guide and adapted to be operated by either of the pistons n' or n'' of the respective cylinders, a relief-valve E having its stem o'' axially in line with said plunger 70 and moved thereby, said valve communicating with the top of the interior of the main air-cylinders B and B' and air-pumps communicating with the bottom of the interior of the cylinders D and D' for the purpose described.

In testimony whereof I have hereunto signed my name this 14th day of May, 1895.

CHARLES H. SHERWOOD. [L.S.]
